UNITED STATES PATENT OFFICE.

HARTWELL W. WEBB, OF CRESSKILL, AND THOMAS VEITCH, OF DUMONT, NEW JERSEY.

STARTING DEVICE FOR INTERNAL-COMBUSTION ENGINES.

1,058,209.

Specification of Letters Patent.

Patented Apr. 8, 1913.

Application filed January 13, 1912. Serial No. 671,095.

To all whom it may concern:

Be it known that we, HARTWELL W. WEBB and THOMAS VEITCH, citizens of the United States, and residents of Cresskill and Dumont, respectively, in the county of Bergen and State of New Jersey, have invented certain new and useful Improvements in Starting Devices for Internal-Combustion Engines, of which the following is a specification.

The present invention relates to starting devices for internal combustion engines, and more particularly to that type in which a supply of combustible mixture of air and hydrocarbon is used for starting purposes.

One of the objects of the invention is to provide a simple and inexpensive device, by means of which a source of energy which is already provided for on all automobiles and other motor vehicles is supplied to the working cylinders of the engine, to be ignited therein by the regular igniting devices of the engine.

Another object of the invention is to produce an electrically operated valve, actuated, preferably, by the regular ignition system of the engine.

A further object of the invention is to produce a simple, inexpensive and efficient joint between the pipe leading from the tank containing a supply of hydrocarbon and the intake manifold pipe of the engine.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and minor details of construction within the scope of the appended claims without departing from the spirit or sacrificing any of the advantages of the invention.

A few of the many possible embodiments of the invention are illustrated in the accompanying drawings, in which:—

Figure 1 is a side elevation, somewhat diagrammatic in form, of an internal combustion engine suitable for use on automobiles showing one way in which the invention may be applied thereto; Fig. 2 is a diagrammatic view of the device with a diagram-

matic illustration of the electric circuits; Fig. 3 is a similar view with modified circuits; Fig. 4 a similar view of a still further modification of the circuits; Fig. 5 is a vertical sectional view of the improved valve; Fig. 6 is a similar sectional view of an enlarged detail of construction of said valve; Fig. 7 is a section taken on line 7—7 of Fig. 6; Fig. 8 is a section taken on line 8—8 of Fig. 6; Fig. 9 is an enlarged vertical sectional view of a modified detail of the valve; Fig. 10 is a section taken on line 10—10 of Fig. 9; Fig. 11 is a vertical section taken through the joint between the manifold and the pipe through which the supply of hydrocarbon is conducted thereto from the auxiliary tank; Fig. 12 is a section taken on line 12—12 of Fig. 11; Fig. 13 is a section taken on line 13—13 of Fig. 11; Fig. 14 is a vertical sectional view of a modification of this joint; and Fig. 15 is a section taken on line 15—15 of Fig. 14.

The invention is shown in the drawings as applied to an internal combustion engine of the four-cycle type, comprising a plurality of cylinders 20, 20, provided with the usual inlets. A supply of combustible mixture is conducted to said inlets through the inlet manifold pipe 21, which is joined with the supply pipe 22 of the carburetor. This engine is mounted immediately forward of the dash-board 23 of an automobile, following common practice. For starting purposes, a source of energy is used which is provided on nearly every motor car, that is the acetylene gas for lighting. This gas is usually stored under pressure in a tank, denoted in the drawings by the numeral 24, connected by a pipe 25 with the intake manifold in a manner hereinafter to be described. The communication between the tank 24 and the intake manifold 21 is controlled by an electrically operated valve 26, shown in detail in Figs. 5 to 8, inclusive, of the drawings. This valve comprises a closed casing 27, from the bottom 28 of which extends downwardly a, preferably, centrally arranged tubular member 29, which communicates with the interior of the tank 24 and is joined with the latter in any suitable manner. The tubular member 29 is provided with a substantially horizontal pipe-like extension 30, to which is connected the pipe 25 leading to the intake manifold. Below the extension 30 is arranged in the tubular member 29 an annu-

lar sharp edged valve seat 31, below which the bore 32 in the tubular member is considerably enlarged. In this enlarged portion of the bore is shiftably arranged a valve 33, fitting snugly the bore and being provided with longitudinally extending peripheral grooves 34, 34. The upper face of the valve 33 holds a disk 35 of compressible material, such as leather, which is held against the sharp edged valve seat 31 by means of a spring 36, bearing against the lower recessed face 37 of said valve and against a perforated stop 38, held stationary within the bore 32 in the tubular member 29.

15 The means for operating the valve 33 comprises an electromagnet of the iron-clad type. The cylindrical wall of the casing 27 is, preferably, made of iron, and so is its bottom 28. The cover 39 of the casing, which 20 is detachable, is preferably made of brass or other non-magnetic material. In the casing is centrally arranged a tubular iron member 40, and flush with the top of the same is held in said casing a disk 41 of brass or other 25 similar non-magnetic material. A magnetizing coil 42 is arranged around the tubular member 40 in the casing, and is thus almost entirely surrounded by iron, whereby the magnetic resistance of the circuit is greatly 30 reduced. In the bore of the tubular member 40 is shiftably arranged a stem 43, made of brass or other similar non-magnetic material, its lower end extending down to the valve 33, and being provided with longitudinally 35 extending peripheral grooves 34 to permit the flow of gas, when the valve 33 is unseated, from the tubular member 29 into the extension 30 and thus into the pipe 25. Upon its upper end the stem 43 carries fix- 40 edly attached thereto an iron disk 45, which is arranged within the cover 39 of the casing above the partition disk 41 thereof. A set-screw 46 projects through a screw threaded hole 47 in the cover 39 into the casing 27, 45 and serves to force the stem 43 downward to unseat the valve 33 and to hold it in such position, at will, for a purpose which will be mentioned hereinafter.

A modification of the valve is shown in 50 Figs. 9 and 10 of the drawings, which differs from that shown in Figs. 5 to 8, inclusive, in that its valve 33' is provided with an upwardly extending stem portion 48, which extends above the valve seat 31 to be actuated 55 by the stem 43 above-mentioned. In this case a ring 35' of leather or similar material is held upon the valve.

In constructions of this type heretofore usually a hole was bored into the manifold, 60 said hole screw threaded and the screw threaded end of the pipe, leading thereto, engaged therewith. Obviously in order to bore a hole into the manifold, the same had to be detached from the engine to prevent 65 the borings from entering the carburetor.

To obviate this defect, the following construction is made use of: The end of the pipe 25 is somewhat flattened and inserted into a radial hole 49 in a gasket 50, which is preferably made of metal, and is of a diameter substantially smaller than that of the flanges 51 and 52 of the manifold 21 and of the supply pipe 22, respectively, so that the uniting screws 53, passing through said flanges, do not engage said gasket. This gasket is provided with a plurality of projections 54, which project either into the manifold 21 or into the supply pipe 22 to center the position of said gasket relative to said manifold and said supply pipe. When the gasket is inserted between the flanges, as shown in Figs. 11 to 13, inclusive, a gastight joint will be provided between the intake manifold and the supply pipe, and it is to be observed that this connection can be made without taking the manifold off the engine, and can be made by anybody, even by unskilled laborers.

In the modification shown in Figs. 14 and 15 the inner end 55 of the pipe 25 extends into the intake manifold, projecting upwardly toward the inlets of the engine.

Firing or ignition in the working cylinders of the engine takes place from the usual spark plugs (not shown in the drawings), such spark plugs being inserted into an electric circuit containing a suitable source of electric energy. On automobiles or motor vehicles either an electric battery or a magneto, or the combination of these two elements are used. In Fig. 2 of the drawings a circuit is shown, in which the source of electric energy comprises a battery 56, one terminal of which is grounded, as shown at 57, while its other terminal is connected by 95 a conductor 58 to the lever 59 of a two-way switch. The contact 60 of this switch is connected by a conductor 61 with the common contact terminal 62 or a distributor 63, from the segments of which lead conductors 100 64, 64 to a spark coil, to be connected then with the spark plugs. The other contact 65 of the two-way switch is connected by a conductor 66 with one of the terminals of the magnetizing coil 42, while its other terminal is connected by a conductor 67 with the ground. The free end of the lever 59 of the switch is provided with a cam shaped face 68, which is adapted to ride over the end of a latch 69, pivoted at 70 to some stationary part of the automobile frame. This latch comprises two parts, that is the arm 71, in which is slidably arranged an arm 72, held by a spring 73 in its outermost position, shown in Fig. 2 of the drawings. A stop 115 74 prevents the latch from swinging over its normal horizontal position. A spring 75 tends to bring the switch lever 59 in contact with the contact point 60.

The operation of the device when inserted 120 125 130

into the circuit shown in Fig. 2 of the drawings is as follows: The acetylene or other hydrocarbon gas under pressure is supplied to the engine cylinders through the intake manifold thereof. Obviously for this reason it must be supplied to said cylinders while the engine is still running and when the ignition system of the engine has been rendered inoperative, or in other words the supply of combustible material used in starting the engine must be forced into the working cylinders of the engine when the latter is about to stop, or more particularly during those few turns of the same when no ignition takes place in the cylinders. During the normal running of the engine, the switch lever 59 contacts with contact point 60, whereby the regular ignition takes place. When the engine is to be stopped, the lever 59 is disengaged from the contact point 60, rendering thereby the ignition system inoperative. The engine will continue to run, however, by the momentum of its fly-wheel, and by forcing the cam-shaped face 68 of the lever 59 over the latch 69 and into contact with the contact point 65, an electric circuit will be closed through the magnetizing coil of the valve 26. As soon as the current flows through this coil, the core of the electromagnet will be magnetized, the disk 45 attracted thereby, by which operation the stem 43 will unseat the valve 33, opening thereby a communication between the tank 24 and the intake manifold 21. As the engine is still running, its cylinders will be filled with a highly explosive charge. In letting the switch lever 59 go, it will be brought by the spring 75 against the free end of the latch into a neutral position, shown in Fig. 2 of the drawings. In order to start the engine, the arm 72 of the latch is forced against the action of the spring toward the arm 71 thereof, whereby the spring 75 will close an electric current by bringing the switch lever 59 into its normal position into contact with contact point 60. Sparking will immediately occur in one of the cylinders, igniting thereby the charge therein and giving thus an initial movement to the engine. After the first ignition has occurred and the initial starting movement given, the charge in the other cylinders will be fired successively in their proper order, the engine then continuing to run in the ordinary manner by drawing combustible mixture from the carburetor.

In Fig. 3 of the drawings, an electric circuit is shown, including a source of electric energy in the form of a magneto 76. This magneto is grounded by a conductor 77 in the usual manner, its brushes being connected by a conductor 78 with the lever 79 of a two-way switch. One of the contact points, that is the contact 80 of the switch is connected by a conductor 81 with a spark coil

82, said spark coil being connected with the spark plugs in the usual manner. The contact point 83 of the switch is connected by a conductor 84 with one of the terminals of the magnetizing coil in the valve 26, its other terminal being connected by a conductor 85 with the ground. The connection shown in Fig. 3 is the one which is maintained during the normal running of the engine. When the engine is to be stopped, the switch lever 79 is brought into contact with contact point 83, whereby a charge of acetylene or other hydrocarbon gas will be supplied to the working cylinders of the engine in the manner hereinbefore described. To start the engine, the lever 79 is drawn over the contact point 80, and the crank-shaft given an initial movement by means of a hand operated crank. In this case, of course, the engine is not entirely self starting, and the supply of acetylene gas is introduced into the cylinders for the purpose of providing a mixture which will explode no matter what the weather conditions be.

In Fig. 4 of the drawings an electric ignition system is shown, which includes two sources of electric energy, that is both a magneto and a battery. The battery is denoted by the numeral 86 and the magneto by the numeral 87. A switch comprising two levers 88 and 89, which are rigidly connected, is provided. The magneto is grounded by a conductor 87', and its brushes connected by a conductor 87'' with the switch lever 89. One terminal of the battery is grounded by a conductor 86', its other terminal being connected by a conductor 86'' with the switch lever 88. The switch levers are adapted to ride over six contact points, which are denoted in their order by the numerals 90, 91, 92, 93, 94 and 95. The contact points 90 and 94 are connected by conductors 96 and 97 with a spark coil 98. Contact points 91 and 93 are neutral points. Contact point 92 is connected by a conductor 99 with one of the terminals of the magnetizing coil of the valve 26, while its other terminal is connected by the conductor 100 with the ground. The contact point 95 is connected by conductor 101 with the ground. The switch levers are held under the action of a spring 102, which tends to bring the lever arm 88 in contact with contact point 90, and thereby the lever arm 89 with the neutral point 93. To prevent the lever from being brought into such positions, a latch construction 69 is provided, which is in all respects identical with that shown in Fig. 2 of the drawings. The switch is shown in its normal position in Fig. 4 of the drawings, in which case the magneto is operative, while the battery 86 is inoperative. Normal ignition will thus take place in the cylinders of the engine. When the engine is to be stopped and at the same time the cyl-

inders are to be filled with acetylene gas, the switch levers are forced downward so that the lever 89 will be brought into contact with contact point 95 and the lever 88 into contact 5 with contact point 92. By this operation, the magneto is short circuited, whereby the ignition system is rendered inoperative; current from battery 86 will, however, flow through conductor 86'', lever 88, conductor 10 99 to the magnetizing coil in the valve 26, from there through conductor 100 to the ground, and from ground through conductors 87' and 86'' to the battery. The valve 33 will thus be operated and the cylinders charged with explosive mixture. In 15 letting go the switch levers, the same are brought into the positions shown in Fig. 4 of the drawings. In order to start the engine, the arm 72 of the latch is forced backward, 20 whereby the spring 102 will bring the arm 88 into contact with contact point 90 and the arm 89 into contact with neutral point 93. Ignition thus takes place by the current supplied from the battery in the manner de- 25 scribed in connection with Fig. 2 of the drawings. After the engine is running for some time, the switch levers are brought back into the positions shown in Fig. 4 of the drawings, when current will be supplied 30 by a magneto.

If the supply of gasolene is exhausted or the carburetor of the engine does not work for some reason, it is possible to let the car run as long as the supply of acetylene lasts 35 by simply screwing up the screw 46 and unseating thereby the valve 33. Combustible mixture will thus enter the cylinders of the engine, which will thus operate in the same manner as when a mixture of vaporized 40 gasolene and air is forced into its cylinders.

What we claim is:—

1. In a starting device, the combination 45 with the intake manifold of an internal combustion engine, of a tank for gas under pressure, a fluid carrying connection between said tank and said manifold, a valve controlling said connection, an ignition system for the engine containing a source of electric energy, electrically operated means for ac- 50 tuating said valve, and means for rendering, at will, said ignition system inoperative and connecting said source of electric energy to

actuate said valve, substantially as and for the purpose specified.

2. In a starting device, the combination 55 with the intake manifold of an internal combustion engine, of a tank for gas under pressure, a fluid carrying connection between said tank and said manifold, a valve controlling said connection, an ignition system for 60 the engine containing a source of electric energy, an electromagnet for actuating said valve, and means for rendering, at will, said ignition system inoperative and connecting said source of electrical energy to actuate 65 said electromagnet, substantially as and for the purpose specified.

3. In a starting device, the combination 70 with the intake manifold of an internal combustion engine, of a tank for gas under pressure, a fluid carrying connection between said tank and said manifold, a valve controlling said connection, an ignition system for the engine containing two independent 75 sources of electric energy, electrically operated means for actuating said valve, and means for rendering, at will, said ignition system inoperative and connecting one of said sources of electric energy to actuate said valve, substantially as and for the purpose 80 specified.

4. In a starting device, the combination 85 with the intake manifold of an internal combustion engine, of a tank for gas under pressure, a fluid carrying connection between 90 said tank and said manifold, a valve controlling said connection, an ignition system for the engine containing two independent sources of electric energy, an electromagnet for actuating said valve, and means for ren- 95 dering, at will, said ignition system inoperative and connecting one of said sources of electrical energy to actuate said electromagnet, substantially as and for the purpose specified.

Signed at New York, in the county of New York and State of New York, this 12th day of January, A. D. 1912.
